US0D1029656S

(12) **United States Design Patent** (10) **Patent No.:** **US D1,029,656 S**
(45) **Date of Patent:** **** Jun. 4, 2024**

(54) **BELTED COVER FOR ELECTRONIC DEVICE**

(71) Applicant: **BANDAI CO., LTD.**, Tokyo (JP)

(72) Inventors: **Erika Yasuda**, Tokyo (JP); **Yuri Okamoto**, Tokyo (JP); **Tadanori Kanemura**, Tokyo (JP); **Megumi Shiina**, Tokyo (JP)

(73) Assignee: **BANDAI CO., LTD.**, Tokyo (JP)

(**) Term: **15 Years**

(21) Appl. No.: **29/816,625**

(22) Filed: **Nov. 23, 2021**

(30) **Foreign Application Priority Data**

May 28, 2021 (JP) ..... 2021-011479 D

(57) **CLAIM**

The ornamental design for a belted cover for electronic device, as shown and described.

DESCRIPTION

FIG. 1 is a perspective view of a belted cover for electronic device showing the new design;

FIG. 2 is another perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a left side elevational view thereof; and,

FIG. 8 is a right side elevational view thereof.

1 Claim, 4 Drawing Sheets
